UNITED STATES PATENT OFFICE.

CHARLES E. WENZ, OF CLIFTON, NEW JERSEY.

VACUUM-PUMP AND CONTROL UNIT FOR PLAYER-PIANO MECHANISMS.

1,289,986.

Specification of Letters Patent.

Patented Dec. 31, 1918.

Application filed June 4, 1918. Serial No. 238,081.

To all whom it may concern:

Be it known that I, CHARLES E. WENZ, a citizen of the United States, residing in Clifton, county of Passaic, and State of New Jersey, have invented certain new and useful Improvements in Vacuum-Pumps and Control Units for Player-Piano Mechanisms, of which the following is a specification.

10 The present invention relates to a power driven vacuum pump mechanism for operating a player piano, and has for its object to provide a device of this character which operates and controls the piano automatically from the exterior thereof, instead of from the interior, and which is adapted to be applied to any conventional tracker board and player piano mechanism.

20 Further objects of the invention are to provide a device of this character in which the power driven vacuum pump and controlling valves are assembled in a unitary structure so that the device can be installed without difficulty, which provides means whereby the playing, stopping and re-rolling may be controlled automatically from the perforated note sheet, and which provides for maintaining a uniform tension or degree of vacuum in the vacuum chamber 25 and action chest at all times, regardless of the position of the tempo lever or the number of perforations in the note sheet, thereby obtaining a smooth and proper action of the mechanism with the driving motor running at a constant speed.

30 With these and other objects in view, the invention consists in certain novel combinations and arrangements of the parts as will more fully appear as the description 35 proceeds, the novel features thereof being pointed out in the appended claims.

40 For a full understanding of the invention, reference is to be had to the following description and accompanying drawings, in 45 which:—

Figure 1 is a side elevation of a power driven vacuum pump and controlling means constructed in accordance with the inven-

tion, portions being broken away and shown in section, and the device being shown in a 50 diagrammatic manner as connected to the tracker board of a player piano.

Fig. 2 is a transverse vertical sectional view through the vacuum pump.

Fig. 3 is an end view of the vacuum pump. 55

Fig. 4 is a side elevation thereof.

Fig. 5 is an enlarged detail view of one of the controlling valves.

Fig. 6 is an enlarged detail view of the automatic tension regulating device. 60

Fig. 7 is a front view of a conventional player piano which is provided with an auxiliary pump and control unit constructed in accordance with the invention.

Corresponding and like parts are referred 65 to in the following description and indicated in all the views of the drawings by the same reference characters.

Referring to the drawings, which illustrate one embodiment of the invention, the 70 numeral 1 designates the base upon which the vacuum pump and automatic valves are mounted. The pump includes two sets of opposed bellows 2 which are arranged upon opposite sides of a vacuum chamber 3, the 75 upper ends of the bellows being operatively connected by pitmen 4 to a crank shaft 5 which is journaled between the upper ends of the standards 6. One end of the crank shaft has a driving connection 7 with an 80 electric motor 8 which is mounted upon the adjacent end of the base 1. The wires 9 of the motor circuit have a hand switch 10 and an automatic switch 11 interposed in the 85 length thereof, the hand switch being closed when it is desired to utilize the device to operate the player piano mechanism, while the switch 11 is arranged to be automatically actuated by a pneumatic 12 when a certain duct 13 in the tracker bar 14 is uncovered by 90 a perforation in the note sheet.

The pump bellows 2 are provided upon the swinging outer sides thereof with outlet ports controlled by the outwardly opening flap valves 15, and upon the inner sides 95 thereof with ports leading to the vacuum

chamber 3, said ports being controlled by inwardly closing flap valves 16. It will thus be obvious that when the bellows of the pump are actuated by the motor air will be exhausted from the vacuum chamber 3 so that the necessary tension can be maintained in this chamber and in the action chest of the mechanism, said chamber being placed in communication with the said action chest by means of a main 17. The action chest and striking pneumatics associated therewith may be of any conventional construction, and it has not been thought necessary to illustrate or describe these in detail in the present application, since they form no part of the present invention.

Arranged above the vacuum chamber 3 are three valve chambers 18 within which vertically reciprocating valves 19 are mounted, said valves being each provided with a stem 20 which terminates at its lower end in a head 21. These heads rest upon flexible diaphragms 22 in pouch chambers 23 and the valves 19 normally engage the valve seats 24, thereby cutting off communication between the valve chambers 18 and the vacuum chamber 3 through the passages 25. The valves normally tend to close by the action of gravity, and the tension of the air in the vacuum chamber serves to hold the valves tightly in a closed position. Independent conduits 26, 27 and 28 lead from the respective valve chambers 18 to the stopping pneumatic 12, replaying pneumatic 29, and rerolling pneumatic 30. In a similar manner independent conduits 31, 32 and 33 lead from the respective pouch chambers 23 to ducts 13, 34 and 35 in the tracker bar 14. Small by-passes 36 are shown as provided between the conduits 31, 32 and 33 and the passages 25, so that when the ducts 13, 34 and 35 in the tracker bar are closed by the note sheet the air in the pouch chambers 23 and vacuum chamber 3 is at the same tension, thereby permitting the valves to drop into a closed position, as indicated by full lines on Fig. 5.

The replaying and rerolling pneumatics 29 and 30 are arranged side by side and have the swinging sides thereof operatively connected as indicated at 37 to the slide rod 38 of the usual finger lever 39 which is provided for controlling the rerolling and replaying mechanism of the piano. As previously explained, the third pneumatic 12 of the controlling mechanism is operatively connected to the switch 11 of the electric motor 8. As long as the ducts 13, 34 and 35 of the tracker bar are closed by the note sheet, the valves 19 remain in a closed position, and the player piano can operate in the usual manner to play the piece of music which has been cut into the note sheet. However, as soon as one of the ducts 13, 34 or 35

is uncovered by an opening in the note sheet, atmospheric pressure is permitted to enter the corresponding pouch chamber 23 under the diaphragm 22, thereby lifting the diaphragm and raising the corresponding valve 19. This places the valve chamber 18 in communication with the vacuum chamber 3 of the pump, with the result that the corresponding pneumatic 12, 29 or 30 is collapsed. When the duct 13 is uncovered the valve 19 which controls the pneumatic 12 is opened, with the result that the said pneumatic is collapsed and the electric switch 11 opened, thereby stopping the driving motor 8. In a similar manner, when the duct 34 is uncovered the valve 19 which controls the replaying pneumatic 29 is opened, with the result that the said pneumatic is collapsed and the slide rod 38 moved in the proper direction for setting the mechanism to replay the piece. In an identical manner the rerolling pneumatic 30 is collapsed when the duct 35 is uncovered, thereby sliding the rod 38 in the opposite direction and setting the mechanism of the player piano to reroll the note sheet. The parts may be constructed so that after being actuated by the pneumatic they will remain in position by the action of friction.

In Fig. 1 the arrangement of the members with relation to a player piano is merely shown in a diagrammatic manner, while in Fig. 7 the device is shown as applied to a player piano in one possible manner. The base 1 with the pump and control valve mechanism mounted thereon is arranged exterior of the piano A so that it can be used in place of the treadle mechanism B, thereby enabling the piano to be driven by power. The vacuum chamber 3 of the pump is connected by the main 17, as previously explained, to the action chest C of the piano. The controlling pneumatics 12, 29 and 30 are conveniently mounted upon the piano case, the pneumatic lever 12 controlling the electric switch 11 for starting and stopping the electric motor 8, while the pneumatics 29 and 30 are operatively connected to the slide rod 38 and move the same back and forth to control the playing and replaying mechanism of the piano. This is usually accomplished manually by means of the finger lever 39, and the pneumatics will not prevent the manual control of the mechanism if it is desired to dispense with the automatic control, this being readily done by closing the several valves 40 and rendering the extra ducts in the tracker board 14 inoperative. The invention thus provides an auxiliary pump and control unit mounted upon a single base 1 which can be positioned exterior of the piano and used in connection with the control pneumatics which are conveniently mounted upon the piano case. A

device is thus provided which can be applied as an attachment to nearly any of the conventional player piano mechanisms.

Manually controlled valves 40 are interposed in the lengths of the conduits 31, 32 and 33, said valves being shown for the purpose of illustration as having the form of slide valves, and as provided with finger pieces 41 by means of which they can be moved in and out. When these valves are opened the operation of the player piano will be automatically controlled by the mechanism which has just been described, although when the valves are closed the passage of the note sheet over the ducts 13, 34 and 35 will not operate the valves 19, and it will be necessary to manually control the player piano mechanism in the usual manner. On the drawing the valves 40 for the conduits 31 and 32 are shown as closed, while the valve for the conduit 33 is shown as open. It will be understood, however, that when the playing of the piano is to be automatically controlled by the three controlling pneumatics 12, 29 and 30, as previously described, all of the valves 40 will be opened.

An automatic tension controlling device is arranged under the vacuum chamber 3. An opening 42 in the bottom of the vacuum chamber is controlled by a slide valve 43, said valve being operatively connected by the lever 44 and link 45 to a pneumatic 46. This pneumatic communicates through a pipe 47 with the vacuum chamber 3, and the collapsing of the pneumatic is resisted by a tension spring 48, one end of the spring being connected to a threaded stem 49 which has an adjusting nut 50 fitted thereon. The tension in this spring can be increased or decreased by tightening or loosening the adjusting nut 50, and this spring holds the pneumatic in an open position until the partial vacuum produced within the vacuum chamber 3 becomes sufficiently strong to overcome the action of the spring and collapse the pneumatic. The collapsing of the pneumatic operates through the link 45 and lever 44 to open the slide valve 43, thereby partially uncovering the opening 42 and permitting a sufficient amount of atmospheric air to enter the vacuum chamber to decrease the tension therein. As soon as the tension of the air in the vacuum chamber has been sufficiently decreased the pneumatic 46 will again expand under the action of the spring 48, the slide valve 43 which is operatively connected to the pneumatic being simultaneously closed. In this manner a uniform tension is maintained within the vacuum chamber and action chest of the player mechanism, regardless of the position of the tempo lever, or the number of openings cut in the note sheet, the electric motor 8 being permitted to run at all times at a uniform speed.

The tension of the spring 48 can be adjusted 65 to regulate the degree of vacuum which is maintained in the vacuum chamber and action chest, and the device can thus be set to operate in the most effective manner in connection with different player piano 70 mechanisms and under different conditions.

The pneumatics 12, 29 and 30 are described and claimed as operatively connected to controlling elements of the player piano, and by the term "controlling elements" as used in 75 the claims is meant some member for controlling the motor or operation of the mechanism, as distinguished from the pneumatics in the action chest which operate the keys of the piano. 80

Having thus described the invention, what I claim as new and desire to secure by Letters Patent, is:—

1. A separate and auxiliary pump control unit for player piano actions, including 85 a base mounted exterior to the piano and independently thereof, a pump mounted on said base so as to be movable therewith and formed with a vacuum chamber, a main connecting the vacuum chamber to the action 90 chest of the piano, a control valve mounted directly upon the pump and carried thereby, a pneumatic arranged remote from the base and controlled by the said valve, an operative connection between the pneumatic and 95 a controlling element of the player piano, and note sheet control means for actuating the valves.

2. A separate and auxiliary pump and control valve unit, including a base mounted 100 exterior to the piano and independently thereof, a pump mounted on said base so as to be movable therewith and formed with a vacuum chamber, a main leading from said vacuum chamber to the action chest of the 105 piano, a pouch chamber and associated valve chamber mounted directly upon the pump and movable therewith, a diaphragm extending across the pouch chamber, a valve mounted within the valve chamber and controlling 110 communication between the said chamber and the vacuum chamber, said valve being controlled by the diaphragm, a conduit between the pouch chamber and the tracker 115 bar, and a remotely mounted pneumatic controlled by the valve and operatively connected to a controlling element of the player piano.

3. The combination with a pneumatic player piano action, including a tracker bar 120 having an extra duct therein, of a vacuum pump formed with a vacuum chamber, a pouch chamber and associated valve chamber being mounted directly upon the vacuum chamber and carried by the pump, a dia- 125 phragm extending across the pouch chamber, a valve mounted in the valve chamber and controlled by the movements of the dia-

phragm, a conduit between the pouch chamber and the extra duct of the tracker bar, a remotely arranged pneumatic operatively connected to a controlling element of the 5 player mechanism, and a conduit between the pneumatic and the valve chamber, communication between the valve chamber and vacuum chamber being controlled by the valve and the pump and valve constituting a unit which is independent of the player piano action.

4. The combination with a pneumatic player piano action, including a tracker bar having a number of extra ducts therein, of a 15 vacuum pump formed with a vacuum chamber, a series of pouch chambers and associated valve chambers mounted directly upon the vacuum chamber and carried by the pump, diaphragms extending across the 20 pouch chambers, valves mounted within the valve chambers and controlling communication between the said chambers and the vacuum chambers, said valves being controlled by the diaphragms, conduits between 25 the respective pouch chambers and the extra ducts of the tracker bar, and a number of remotely mounted pneumatics operatively connected to different control elements of the player mechanism and in communication 30 with the valve chambers, the vacuum pump and control valves being assembled as a complete unit which is independent of the player piano action.

5. A separate and auxiliary pump and 35 control valve unit for player pianos, including a base mounted exterior to the piano and independently thereof, a pump mounted on said base so as to be movable therewith and formed with a vacuum chamber, a valve 40 chamber mounted directly upon the vacuum chamber and carried by the base, a valve within the valve chamber, a remotely arranged pneumatic controlled by the valve and operatively connected to a controlling 45 element of the player mechanism, and note sheet control means for actuating the valves, the pump and control valve being assembled as a unit which is mounted upon the base and is movable independently of the player 50 piano.

6. An auxiliary pump and control unit for player piano actions, including a base, adapted to be mounted exterior of the piano and individually thereof, a pump mounted 55 on said base and formed with a vacuum chamber, a pouch chamber and superposed valve chamber arranged at one side of the vacuum chamber, and mounted directly thereon so as to be carried by the base, a 60 diaphragm extending across the pouch chamber, a valve mounted within the valve chamber and controlling communication between the said chamber and the vacuum chamber, said valve being controlled by the

diaphragm, a conduit between the pouch 65 chamber and the tracker bar, a pneumatic remote from the base and operatively connected to a controlling element of the player piano action, and a conduit between the pneumatic and the valve chamber.

7. An auxiliary pump and control unit for 70 player piano actions, including a base adapted to be mounted exterior of the piano and individually thereof, spaced standards projecting from the base, a crank shaft journaled between the standards, opposed sets of bellows arranged on opposite sides of the standards and operatively connected to the crank shaft, a vacuum chamber being provided between the bellows and operatively 75 connected thereto, a series of valve chambers arranged above the vacuum chamber and mounted directly thereon, valves mounted within the valve chambers and controlling communication between the same and the 80 vacuum chamber, pneumatics remote from the base and operatively connected to controlling elements of the player piano mechanism, conduits between the pneumatics and the respective valve chambers, and note sheet 85 controlled means for selectively actuating the valves.

8. An auxiliary pump and control unit for 90 player piano actions, including a base adapted to be mounted exterior of the piano and 95 individually thereof, standards projecting from said base, a crank shaft journaled between the standards, opposed sets of bellows operatively connected to the crank shaft, a vacuum chamber being provided 100 between the two sets of bellows and operatively connected thereto, a series of pneumatics arranged remote from the base and operatively connected to controlling elements 105 of the player piano mechanism, conduits leading from the pneumatics to the vacuum chamber, valves mounted directly upon the vacuum chamber and controlling the conduits, note sheet controlled means for selectively actuating the valves, a tension controlled valve for the vacuum chamber, and means for automatically actuating the said 110 valve according to the tension in the vacuum chamber.

9. An auxiliary pump and control unit for 115 player piano actions, including a base adapted to be mounted exterior of the piano and individually thereof, standards projecting from said base, a crank shaft journaled between the standards, a pair of opposed sets 120 of bellows mounted upon opposite sides of the standards and operatively connected to the crank shaft, a vacuum chamber being provided between the two sets of bellows and operatively connected thereto, valve 125 chambers being provided at one side of the vacuum chamber and mounted directly thereon, valves mounted within the valve

chambers and controlling communication between the said chamber and the vacuum chamber, a series of pneumatics arranged remote from the base and operatively connected to controlling elements of the player piano mechanism, note sheet controlled means for selectively actuating the valves,

a tension controlling valve at one side of the vacuum chamber, a pneumatic in communication with the vacuum chamber and operatively connected to the valve, and yielding means resisting the action of the pneumatic. ¹⁰

CHARLES E. WENZ.
